UNITED STATES PATENT OFFICE.

JOHN L. WHEELER AND EDWIN T. NUGENT, OF ST. LOUIS, MISSOURI, ASSIGNEES TO THE MEASUREGRAPH COMPANY, OF ST. LOUIS, MISSOURI, A CORPORATION OF DELAWARE.

MECHANISM FOR INSURING CORRECT STARTING POINT IN FABRIC-MEASURING MACHINES.

Application filed April 4, 1924. Serial No. 704,128.

To all whom it may concern:

Be it known that we, JOHN L. WHEELER and EDWIN T. NUGENT, citizens of the United States, residing in the city of Saint Louis and State of Missouri, have invented new and useful Improvements in Mechanism for Insuring Correct Starting Point in Fabric-Measuring Machines, of which the following is a specification.

10 This invention relates to an improvement in fabric measuring machines designed to secure, on the one hand, accuracy of measurement, and on the other, to prevent the clerk operating the same from accidentally or carelessly giving to the customer a greater quantity of material than the amount actually paid for.

The invention is applicable particularly to the fabric measuring machine known as 20 "The Measuregraph," and while such machine and improvements therein is involved in a large number of prior patents and pending applications, we refer to the patent of Hosch, No. 1,454,285, dated May 8th, 25 1923, as showing the type of machine referred to, and to which our invention relates.

In the use of such a measuring machine, 30 the operator grasps the end of the fabric with the fingers of his right hand, and holding the body of the fabric with his left hand, inserts the edge of the fabric in the pass between the rollers. He then draws the fabric through with his left hand 35 to bring the edge thereof substantially in line with a cutting blade located at the side of the machine and, in a further movement, his thumb engages a plate, indicated as 40 "22," in said prior patent, which releases the presser roller which thereupon is lowered by spring pressure into engagement 45 with the fabric resting on the measuring roller, thus placing the machine in operative condition for measuring, and as the fabric is pulled between the rollers, the measuring roller is operated to actuate the indicating and cost computing mechanisms.

With a careful operator the measurement 50 may be accurately made and no loss to the shop-keeper results. A careless, or indifferent operator, however, will frequently take two or three inches of goods between the fingers of the right hand in adjusting

the fabric in the machine, instead of grasping it at the edge, and when the actuating plate is engaged by the thumb to lower the presser roller, as described, this excess amount of material will project beyond the side of the machine and will not figure in the measuring operation, with the result 60 that it is donated to the purchaser and, of course, represents a loss to the shop-keeper.

In the sale of materials of moderate values, this loss would not be very considerable but in the case of fabrics selling 65 at anywhere from \$5.00 to \$10.00 a yard, or more, and with a large number of sales, the resultant loss to the shop-keeper is very considerable.

The invention herein disclosed prevents 70 such action by the clerk in the ordinary measuring operation by rendering it impossible to lower the presser roller,—a necessary pre-requisite to the measuring operation,—until the edge of the goods has been 75 properly positioned relative to the cutter or marker located at the side of the machine, to insure that when the fabric is drawn through the machine, in a measuring operation, and slit by the cutter at the 80 termination of the measured portion, the amount of goods delivered to the customer will correspond exactly with the amount indicated by the measurement indicators of the machine, and paid for by the purchaser. 85

The broad idea of the invention consists in the application of certain mechanism associated with the presser roller and the mechanism for operating the same, which enables the material itself, inserted in the 90 machine, to act as an obstruction to the lowering of the presser roller, and thereby prevent the machine from being placed in operative condition for measuring, until the edge of the goods has been correctly positioned for correct measurement. Other objects of the invention, which will be more clearly understood from the detailed description to follow, relate to the construction, combination and operation of parts 95 whereby the broad object of the invention is attained.

The invention is illustrated in the accompanying drawing in which—

Figure 1 is a plan view of the measuring 105 machine to which our invention relates, de-

signed to show the manner of positioning the edge of the fabric to be measured in the machine, and the manner by which an actuating plate is operated by the thumb of 5 the operator to lower the presser roller;

Figure 2 is a cross-section on the line 2-2 of Figure 1;

Figure 3 is a view in side elevation with the casing of the machine partly broken 10 away to illustrate the mechanism of our invention as applied to the machine, the parts being shown in the position they occupy after the presser roller has been lowered;

15 Figure 4 is a detached view in side elevation showing the manner in which the cutter or marker of Figure 3 co-operates with our mechanism to raise or reset the presser roller; and

20 Figure 5 is a view in broken side elevation with the cutter removed, showing the parts in the position they occupy in Figure 4 and just prior to their actuation to release the presser roller.

25 Referring now to the drawings, the numeral 1 indicates the casing of the fabric measuring machine enclosing fabric measuring and cost computing mechanism and means for operating the same. The indicating mechanism comprises, generally, a numbered dial 2, pointers 3 (one being hidden) movable over said dial and charts 4 containing computations (not shown, the charts being at the zero position) movable 30 past price scales 5. The hands 3 and charts 4 are operated by mechanism (not shown) actuated from a measuring roller 6, Figures 2 and 3, with which co-operates a presser roller 7, the faces of these rollers being 35 designed to engage centrally of an opening 8 provided in one end of the machine for the entrance of the fabric. The presser roller 7 is rotatably mounted in a frame 9 which is pivotally mounted at its ends at points 40 corresponding to the numeral 10 of Figure 2 in the frame of the machine, and said frame is provided with an operating arm or lever 11 to which is secured one end of a coil spring 12, the other end of which is secured 45 to the frame. This spring normally tends to turn the presser roller 7 downward into engagement with the measuring roller 6.

50 The construction ~~so~~ far described is well known and we ~~will~~ now proceed to describe the mechanism of our invention by which the presser roller frame is actuated to be raised and lowered. The lever 11 projects through a rectangular opening 13 in one of 55 the side frame members of the machine, indicated at 14, and positioned to co-operate with said lever is one arm 15 of a toggle lever which is provided at its lower end with a shoulder 16 adapted to engage the 60 upper side of the lever 11. The arm 15 is

pivotal connected at 17 to the lower end of a short arm 18 constituting the second member of the toggle lever, the upper end of said arm being pivotally mounted at 19 on the frame plate 14. When the toggle 70 lever is straightened, the arm 15 pressing down on the end of the lever 11 will operate to rock the frame 9 on its pivots 10 and raise the presser roller 7, such position of the parts being shown in Figure 2. When 75 the toggle lever is broken, or is in the position shown in Figure 3, the spring 12 pulling up on the lever 11 operates to rock the frame 9 and throw the presser roller 7 downward into engagement with the measuring 80 roller, or the fabric in position thereon, or to the position shown by dotted lines in Figure 2. The manner of operating the toggle lever will now be described.

Positioned in the rectangular opening 13, 85 and accessible through a corresponding opening in the outer casing 1, (not shown but indicated by the position of the thumb in Figure 1) is an actuating plate 20 which has upwardly extending arms 21 pivotally 90 mounted at 22, Figure 2, in the frame of the machine. Projecting outwardly from the upper end of one of these arms is a lever arm 23, Figures 2 and 3, which engages in an aperture 24 provided in the 95 lower end of a link 25 which, at its upper end, is pivotally connected at 26 intermediate the ends of a throw lever 27 which is pivotally mounted at one end, as indicated at 28, Figure 5, on the frame plate 14. The 100 opposite end of the throw lever 27 is provided with a stud 29 which is adapted to work in a vertically disposed slot 30 provided in a locking bar 31. In order to provide for movement of the inner end of the 105 throw lever 27, or that at the right as shown in Figure 5, directed toward the upper end of slot 30 in locking bar 31, we provide a coil spring 32, one end of which is secured to the stud 29 on said throw lever, and the 110 other end with stud 33 provided on the upper end of the locking bar. The purpose of this construction will presently appear.

The locking bar 31 is designed for vertical movement and to this end it is slidably mounted on the frame plate 14 through the medium of a vertically disposed slot 34 provided intermediate its ends with a set screw 35, the head of which bears against the face of the locking bar and the stem of 115 which passes through said slot and engages in the frame plate 14. A coil spring 36 is connected at its lower end, as indicated at 37, to the locking bar and at its upper end to the frame plate 14, as indicated at 38. 120

The locking bar 31 has two functions, one, that of permitting the machine to be placed in operative condition for measuring, by breaking the toggle levers 15, 18, and the other, that of preventing such action should 125 130

the cloth not be in the proper position for measuring. To break the toggle lever we provide the following mechanism shown particularly in Figures 3, 4 and 5:

5 The numeral 39 indicates a dog which is pivotally mounted at its lower end, as indicated at 40, near the lower end of the frame plate 14. At its upper end the dog 39 is provided with a set screw 41 which may be 10 secured in any adjusted position in the end of the dog by a lock nut 42. The end 43 of the set screw is normally in engagement with a stud 44 projecting from the side of the toggle levers 15, 18 at the knuckle there- 15 of, the stem of said stud forming the pivotal connection between the two members of the toggle levers. The outer side of said dog or that to the right in Figure 3, is provided with a cam surface 45. The locking bar 31 20 is provided on its side facing the dog 39 with a projection 46 having a cam edge 47 adapted to engage with the cam edge 45 of the dog 39. The operation of the parts as thus far described is as follows:

25 Assuming the parts to be in the position shown in Figures 4 and 5, and it being desired to measure a length of fabric, the latter is inserted in the opening 8 and passed between the rollers 6 and 7. The presser roller is, of course, in the raised position as shown by Figure 2. The operator pulls the cloth inward, or toward the machine, until the edge is in the position desired and with his thumb pushes inward the 30 thumb plate or actuator 20. In this movement the lever 23 pulls the link 25 downward, which causes the outer end of the throw lever 27 to move downward. The outer end of this throw lever being connected 35 by the spring 32 with the lock plate 31, the latter is moved downward until its cam edge 47 engages the cam edge 45 of dog 39, which is the position shown in Figure 5, whereupon a slight further movement of the locking plate forces the dog inward and the end 43 of the set screw carried by said dog pushes the stud 44 of the toggle lever inward, thereby 40 breaking the joint of said lever and permitting the spring 32 (Figure 2) to throw the presser roller downward into engagement with the fabric. The cloth is then pulled between the rollers and as the measuring roller 6 is rotated, the indicators 3 and charts 4 are moved to show the length 45 measured and the cost of the measured length of material.

The machine illustrated is provided with means for slitting the edge of the fabric at the termination of the measured portion. 50 To this end a knife 48 controlled by a spring 49 and provided at its outer end with a thumb plate 50, is pivotally mounted in the machine at 51 in a manner to co-operate, when depressed, by pushing on the thumb plate 50, with a fixed blade 52 secured on

the machine. In the operation of this knife, in the type of machine referred to, the presser roller is adapted to be raised out of contact with the measuring roller. This 70 operation also occurs in connection with the mechanism we have described and with this in view, the knife 48, Figure 4, is provided with a contact arm 53 which, when the knife is pushed downward, is adapted to engage the stud 44 of the toggle levers 15, 18, and 75 restore said toggle levers to the straight position, as shown in Figure 4.

We will now describe the manner of preventing the operation of measuring when the end of the fabric has not been positioned 80 correctly for accurate measurement. Such means comprises a rectangular aperture 54, Figures 1, 2 and 5, which is adapted to co-operate with the lower end portion of the locking bar 31. This aperture is located 85 near the edge of the casing 1 in that part thereof forming the bottom of the slot 8, and near the edge of said slot in line with the knife 48. The aperture 54 thus constitutes a fixed starting point for the measuring operation. It will now be seen that as the fabric is moved inward to bring its end to the measuring position, in the event the end of the fabric should not be drawn into the machine a sufficient distance to uncover 90 the aperture 54, the lower end of the locking bar cannot enter said aperture, and therefore operates to prevent the machine being placed in operative condition for measuring, and in the operation of the actuator 20 by the 95 thumb the outer end of the throw lever 27 will simply move downward against the resistance of the spring 32; hence the locking bar cannot engage the dog 45 to break the toggle lever and permit the presser roller 100 to be lowered. It is, therefore, necessary for the operator to arrange the fabric in the machine so as to uncover the aperture 105 54. This insures that the end of the fabric will be located at the proper position to insure that the amount of fabric drawn through the machine will correspond with the amount indicated on the measuring dial. Referring to Figure 3, the numeral 55 indicates a stud which limits the upward movement of the member 18 of the toggle lever 110 and the numeral 56 indicates a headed stud which guides the lower end of the member 15 of the toggle lever and which also acts as a stop for limiting the inward movement 115 of the dog 39.

In the accompanying drawing, we have shown, and in the above specification described, the preferred, and the best known, embodiment of our invention. It will be understood, however, that our invention is not limited in application to the particular form of machine described, or to the exact details of construction shown and described. For 120 example, it will be obvious that the aper- 125

ture 54 could be of other shape than rectangular, and that the locking bar 31 could be correspondingly shaped. It will also be obvious that the invention could be applied to machines in which the presser roller is lowered in moving it away from the measuring roller, as well as to the type of machine shown where the presser roller is raised.

We claim:

10. 1. In a fabric measuring machine of the class described, having means for measuring from a fixed starting point on the machine, and means for placing the machine in operative or inoperative condition for measuring, means in line with said fixed starting point and movable in placing the machine in operative condition for measuring and operating to prevent the machine from being placed in such condition when the end of the fabric to be measured projects beyond said latter means in the direction of the measuring movement of the fabric.
15. 2. In a fabric measuring machine of the class described, in combination with the presser roller, means for holding the same away from the measuring roller, and means under the control of the operator for releasing the holding means, mechanism associated with said releasing means and adapted to engage the fabric, inserted in the machine to be measured, when the end of the fabric projects beyond a point on the machine fixing the starting point for the measurement of the fabric and thereby prevent operation of said releasing means.
20. 3. In a fabric measuring machine of the class described, in combination with the presser roller, means for holding the same away from the measuring roller, and means under the control of the operator for releasing the holding means, mechanism associated with said releasing means and adapted to engage the fabric, inserted in the machine to be measured, when the end of the fabric projects beyond a point on the machine fixing the starting point for the measurement of the fabric and thereby prevent operation of said releasing means.
25. 4. A fabric measuring machine of the class described, having a measuring roller and a presser roller and a casing enclosing the same affording an opening to the pass between the rollers, said casing having an aperture in the part forming the bottom of said opening fixing the starting point for the measurement of the fabric, means for holding the presser roller in an elevated position, means under the control of the operator for releasing the holding means, a movable member associated with said releasing means and movable thereby across the path of movement of the fabric to be measured at a point on the machine fixing the starting point for the measurement of the fabric, and adapted to engage the fabric when the end of the fabric projects beyond said point and prevent operation of said releasing means.
30. 5. In a fabric measuring machine of the class described, having a measuring roller and a presser roller and a casing enclosing the same affording an opening to the pass between the rollers, said casing having an aperture in the part forming the bottom of said opening fixing the starting point for the measurement of the material, an element movable to place the machine in condition for measurement, and a member cooperating with said element and movable thereby to cause a part of said member to enter said aperture, said member being adapted to engage the material, inserted in the machine to be measured, when the end thereof projects over said aperture and thereby prevent

effective operation of said starting element.

5. In a fabric measuring machine of the class described, in combination with the presser roller, means for holding the same away from the measuring roller, and means under the control of the operator for releasing the holding means, mechanism associated with said releasing means and adapted to engage the fabric, inserted in the machine to be measured, when the end of the fabric projects in the direction of the measuring movement of the fabric beyond a point on the machine fixing the starting point for the measurement of the fabric and thereby prevent operation of said releasing means.

6. In a fabric measuring machine of the class described, in combination with the presser roller, means for holding the same away from the measuring roller, and means under the control of the operator for releasing the holding means, a vertically movable member associated with said releasing means and movable thereby across the path of movement of the fabric to be measured, and adapted to engage the fabric when the end of the fabric projects beyond a point on the machine fixing the starting point for the measurement of the fabric and thereby prevent operation of said releasing means.

7. A fabric measuring machine of the class described, having a measuring roller and a presser roller and a casing enclosing the same affording an opening to the pass between the rollers, said casing having an aperture in the part forming the bottom of said opening fixing the starting point for the measurement of the fabric, means for holding the presser roller in an elevated position, means under the control of the operator for releasing the holding means, and a vertically movable member associated with said releasing means and movable thereby to cause its lower end to enter said aperture, said member being adapted to engage the fabric, inserted in the machine to be measured, when the end of the fabric projects over said aperture and thereby prevent operation of said releasing means.

8. In a fabric measuring machine of the class described, in combination with a pivotally mounted frame having a presser roller rotatably mounted therein, a spring tending normally to move said frame to place said roller in operative position, an arm on said frame, a toggle lever engaging said arm and adapted, when straightened, to depress the same and hold the presser roller frame and roller in inoperative position, means under the control of the operator for breaking said toggle lever to permit said frame to be actuated by its spring to move the presser roller, and means adapted to engage the fabric, inserted in the machine to be measured, when the end of the fabric projects beyond a point on the machine

- fixing the starting point for the measurement of the fabric and thereby prevent operation of said toggle breaking means.
9. In a fabric measuring machine of the 5 class described, in combination with a pivotally mounted frame having a presser roller rotatably mounted therein, a spring tending normally to lower said frame, an arm on said frame, a toggle lever engaging said 10 arm and adapted, when straightened, to depress the same and hold the presser roller frame elevated, means under the control of the operator for breaking said toggle lever to permit said frame to be actuated by its 15 spring to lower the presser roller, and means adapted to engage the fabric, inserted in the machine to be measured, when the end of the fabric projects beyond a point on the machine fixing the starting point 20 for the measurement of the fabric and thereby prevent operation of said toggle breaking means.
10. In a fabric measuring machine of the class described, in combination with a pivotally mounted frame having a presser roller 25 rotatably mounted therein, a spring tending normally to lower said frame, an arm on said frame, a toggle lever having one member engaging said arm and operating, when 30 the toggle lever is straightened, to depress the arm and raise said frame and presser roller, a vertically movable member, means under the control of the operator for lowering the same to cause its lower end to pass 35 across the path of movement of the fabric to be measured, means on said member for breaking the toggle lever when said member is lowered and permit said spring to lower the presser roller, the lower end of said 40 member being adapted to engage the fabric, inserted in the machine to be measured, when the end of the fabric projects beyond the lower end of said member and thereby prevent sufficient movement of said member 45 to effect breaking of the toggle lever.
11. In a fabric measuring machine of the class described, in combination with a pivotally mounted frame having a presser roller rotatably mounted therein, an arm on said 50 frame, a toggle lever having a member engaging said arm and operating, when the toggle lever is straightened, to depress the arm and raise the presser roller frame, a spring operating to lower the presser roller 55 frame when the toggle lever is broken, a pivotally mounted dog having an end normally engaging the knuckle of said toggle lever, a vertically movable bar having a member for engaging said dog when the bar 60 is lowered to effect breaking of said toggle lever, means under the control of the operator for lowering said bar to break the toggle lever and thereby cause the lower end of said bar to pass across the path of movement of the fabric to be measured, the lower 65
- end of said bar being adapted to engage the fabric, inserted in the machine to be measured, when the end of the fabric projects beyond the lower end of the bar and thereby prevent the member on said bar from actuating said dog to break said toggle lever. 70
12. In a fabric measuring machine of the class described, in combination with the presser roller, means for holding the same away from the measuring roller, and means under the control of the operator for releasing the holding means, a vertically movable bar having a yielding connection with said releasing means and adapted to have its lower end engage the fabric, inserted in the machine to be measured, when the end of the fabric projects beyond the lower end of the bar and thereby prevent operation of 80 said releasing means. 85
13. In a fabric measuring machine of the class described, in combination with the presser roller, means for holding the same away from the measuring roller, and means under the control of the operator for releasing the holding means, a vertically movable bar, a spring normally holding the same in a raised position, a lost-motion connection between said bar and said releasing means, the lower end of the bar being movable in the operation of the releasing means across the path of the fabric to be measured, and being adapted to engage the fabric when the end thereof projects beyond the lower end of said bar and thereby prevent operation of 90 said releasing means. 95
14. In a fabric measuring machine of the class described, in combination with a pivotally mounted frame having a presser roller rotatably mounted therein, an arm on said frame, a toggle lever having one member engaging said arm and operating, when the toggle lever is straightened, to depress said arm and raise said frame, a spring operating 100 to lower said frame when the toggle lever is broken, an actuating member movable by the operator, a pivotally mounted throw-lever adapted to have its outer end lowered when said actuator is operated, a vertically movable bar having a yielding connection with said throw-lever, a spring normally holding said bar in an elevated position, a pivotally mounted dog having an end engaging the knuckle of said toggle lever, and a member on said bar operating, 110 when the latter is lowered, to engage said dog and move the same to break the toggle lever, the lower end of said bar being movable by said throw-lever across the path of movement of the fabric to be measured, and being adapted to engage the fabric when the end thereof projects beyond the lower end of said bar and thereby prevent lowering of said bar a sufficient distance to move 115 said dog. 120
- 125
- 130

15. In a fabric measuring machine of the class described, in combination with a pivotally mounted frame having a presser roller rotatably mounted therein, an arm on said frame, a toggle lever having a member engaging said arm and operating, when the toggle lever is straightened, to depress the arm and raise said frame, means under the control of the operator for breaking said toggle lever, including a vertically movable bar, the lower end whereof is movable, in the operation of breaking the toggle, across the

path of movement of the fabric to be measured, and being adapted to engage the fabric when the end thereof projects beyond the lower end of the bar and prevent breaking of the toggle to permit the presser roller to be lowered, and manually operable means for straightening said toggle lever.

In testimony whereof, we have hereunto set our hands.

JOHN L. WHEELER.
EDWIN T. NUGENT.
